ALFRED SONDHEIMER, OF BROOKLYN, NEW YORK.

TALKING MACHINE.

Application filed January 3, 1918. Serial No. 210,133.

To all whom it may concern:

Be it known that I, ALFRED SONDHEIMER, a subject of the Emperor of Germany, residing at Brooklyn, in the county of Kings and State of New York, have invented certain new and useful Improvements in Talking Machines, of which the following is a specification.

Some of the objects of this invention are 10 to provide an improved collapsible talking machine which may be folded from an operative condition into a compact inoperative condition for transportation or storage; to provide in a talking machine an improved 15 mounting for a tone arm; to provide an improved sound amplifier; to provide in a talking machine improved means for modifying the sounds produced; to provide in a talking machine an improved casing arranged 20 to enclose the motor when the machine is in operation and to enclose the motor and also various other parts when the machine is not in operation; to provide an improved motor for talking machines; to 25 provide in a motor an improved brake and governor; and to provide other improvements, as will appear hereinafter.

In the accompanying drawings, Fig. 1 is 30 a side elevation of a talking machine constructed in accordance with this invention and in its collapsed or folded inoperative condition; Fig. 2 a top plan view of the same; Fig. 3 a fragmentary side elevation of the same, partly in vertical section and 35 showing the parts in operative position; Fig. 4 a fragmentary top plan view of the same showing some of the parts in their inoperative positions within the casing; Fig. 5 an enlarged transverse vertical section on line 5—5 of Fig. 3; Fig. 6 an enlarged vertical central section through portions of this improved machine; Fig. 7 a transverse section on line 7—7 of Fig. 6; Fig. 8 an end view 40 partly in vertical section of a detail of the parts shown in Fig. 6; Fig. 9 an enlarged fragmentary perspective, partly in vertical section, of the lower portion of the machine; and Fig. 10 is a horizontal section on line 45 10—10 of Fig. 6.

Referring to the drawings, one embodiment 50 of this invention comprises a talking machine including an oblong rectangular casing 25 having a flat bottom wall 26, two vertical parallel end walls 27 and 28, two 55 vertical parallel side walls 29 and 30, and a top wall or cover 35, which overlaps the up-

per edges of the end walls 27 and 28 and side walls 29 and 30, and covers the entire area between the outer surfaces of the end walls 27 and 28 and side walls 29 and 30. 60 The top wall or cover 35 includes a comparatively wide section 36 which is secured fixedly in position in any suitable manner over the front end of the body portion of the casing, a relatively narrow section 37 which 65 is fixedly secured over the rear end of the body portion of the casing, an auxiliary movable section 38 which is hinged as at 39 to the front section 36 to open outwardly with respect thereto, and a main movable 70 section 45 which is hinged as at 46 to the rearmost section 37 to open outwardly with respect thereto. The main movable section 45 forms a part of an amplifier, as will appear hereinafter, and the auxiliary section 75 38 is arranged to hold the sound amplifier either in a predetermined operative position or in a predetermined inoperative position, as will appear hereinafter. The casing 25 is preferably provided with a strap 47 which 80 is terminally secured to the outer surface of one side 29 of the casing to provide a handle whereby the casing may be conveniently carried. The top sections 36, 38 and 45 are preferably in the form of sounding boards.

For rotating a sound record, there is enclosed within the front end of the casing 25 a motor 50 which is arranged beneath and rigidly supported by a normally horizontal motor board 55 which extends across the full width of the casing 25 and which is removably supported upon two cleats 56 and 57 which are rigidly secured against the inner surfaces of the side walls 29 and 30 95 respectively. This motor board 55 is preferably, although not necessarily, in the form of a sounding board. The motor 50 includes two horizontal, rectangular plates 58 and 59 which are spaced vertically apart by four vertical sleeves 60 through which extend respectively four vertical bolts 61, the upper ends of which project upwardly through the motor board 55 and are rigidly clamped in position by four nuts 62. The lower ends 100 of these bolts 61 are headed or riveted over the lower surface of the lower plate 59, and these bolts act to clamp the two plates 58 and 59 rigidly in position. The motor 50 also includes a spring barrel 63 of any well 110 known or suitable construction arranged around a vertical rotary spring barrel shaft

64 to be rotated about a fixed vertical axis by one or more springs contained within the spring barrel. These springs are arranged to be wound up in a well known manner by any suitable means actuated by a detachable crank 65, which when in operation extends through an opening 65' provided therefor in one of the side walls 29. The spring barrel 63 actuates a gear 66 which actuates a pinion 67 rigid with a countershaft 68, and which has rigid therewith a gear 69 which engages a pinion 70 rigid with a vertical turntable spindle 71 which is held against vertical movement, and the upper end 72 of which extends loosely through a circular opening 73 provided therefor in the motor board 55, and projects loosely within and is coaxial with a circular opening 73' provided therefor in the front section 36 of the top wall 35, the upper end 72 of the turntable spindle 71 terminating slightly below the plane of the upper surface of the front section 36 of the top wall and being preferably tapered upwardly to receive the turntable.

Arranged above the top wall 35 is a turntable or record support 75 which is provided with a downwardly extending hub 76 rigid therewith and having an inwardly tapering socket 77 adapted to fit snugly over the upper end of the turntable spindle 71, and loosely within the openings 73 and 73' in the motor board 55 and top section 36 respectively. The turntable 75 is provided centrally upon its upper side with a centering pin 78 rigid with the turntable and arranged to project through the opening which is ordinarily provided in the center of the sound record 80 which the turntable is intended to support. The turntable 75 is preferably provided with a marginal flange 81 integral therewith and is preferably slightly less in diameter than the width between the inner surfaces of the side walls 29 and 30 of the casing 25, and is arranged so that it may be readily removed from the turntable spindle 71 and stored in an inverted, inclined position beneath the lower horizontal plate 59 of the motor, and held in position by means of a spring clip 85, one end of which is rotatably clamped against the upper surface of the bottom wall 26 by a screw 86 or other suitable means, and the other end of which engages loosely in a recess 87 provided therefor in a lug 88 which is provided for this purpose upon the under side of the turntable 75 to which it is rigidly secured.

The spring 85 is provided with two longitudinal crimps, one of which is arranged to embrace the rim 81 of the turntable 75, and the other of which is arranged to embrace and press down upon the winding crank 65 and hold it securely in an inoperative position against the under side of the turntable, and with its opposite ends against the in-

ner surface of the flange 81 of the turntable, as shown in full lines in Figs. 4 and 9. When the turntable 75 is thus arranged in its inoperative position, as shown in dotted lines in Fig. 3 and in full lines in Fig. 5, the hub 76 of the turntable extends upwardly and fits snugly in a slot or recess 89 provided therefor in the rear edge of the lower plate 59 of the motor.

For reproducing sounds from a record 80 mounted upon the turntable 75, a sound box 90 of any well known or suitable construction is provided. The sound box shown in the drawings includes a cylindrical casing 91 provided with a vibratory circular diaphragm 92 which is arranged to be vibrated by a stylus bar 93 which is arranged to oscillate with respect to the casing 91 about a fixed axis, and which is provided at its outer end with a removable stylus 94 which is clamped in position by a set screw 95. The sound box 90 is mounted upon the free end of a tapering hollow sound box arm or tone arm 100 and is preferably arranged to be rotatably adjustable with respect to the arm 100 through 90 degrees so that the sound box may be arranged either with its diaphragm 92 substantially perpendicular to the plane of the record 80 and with the stylus 94 correspondingly arranged to cooperate with a record of the "lateral" or "zig-zag" type, or with the diaphragm rotated through 90 degrees from its vertical position and into a position arranged in a plane oblique to the plane of the record 80 and with the stylus 94 correspondingly positioned to cooperate with a "vertical" or "hill and dale" record. The sound box is arranged to be held in either position of adjustment by means of a knurled set screw 105 which extends loosely through a slot 106 provided therefor in the neck of the sound box and is threaded into the free end of the tone arm 100. For supporting the larger end of the tone arm 100, the larger end of the tone arm is slightly reduced in diameter and is of a cylindrical form and fits snugly but rotatably in a cylindrical socket 109 provided therefor in one end of a tubular carrier 110, the other end of which is enlarged and is in the form of a zone of a sphere externally, providing a "ball" 111. The carrier 110 is provided with a longitudinal opening 110', the longitudinal axis of which is in the form of an obtuse angle so that when the sound box 90 is in a central position on the record, the outlet of the carrier will be centrally arranged as shown in Fig. 10.

The tone arm 100 is arranged to be freely rotatable with respect to the carrier 110 about the longitudinal axis of the tone arm and through about 100 degrees to permit the sound box to be inverted from the position shown in Fig. 3 in which its diaphragm is

vertical, to a position in which the diaphragm will be in a plane above the tone arm and in a plane slightly inclined with respect to the plane of the record 80. This rotary movement of the tone arm 100 with respect to its carrier 110 is controlled and limited by means of a set screw or stop 112 which extends loosely through an oblong arcuate slot 113 provided therefor in the tubular carrier 110 and is threaded into the reduced cylindrical portion of the tone arm 100. The stop 112 is ordinarily so adjusted as to permit the tone arm 100 to be rotated about its longitudinal axis freely between the limits of rotation determined by the stop 112 and the end walls of the slot 113, and the stop 112 and the slot 113 are so arranged that when the tone arm 100 is at the limit of its movement in one direction, the diaphragm 92 of the sound box 90 will be vertical, and so that when the tone arm 100 is at the limit of its movement in an opposite direction, the sound box 90 will rest in an inoperative inverted position above the tone arm 100 and with its diaphragm 92 slightly inclined with respect to the horizontal. The tone arm 100 and the sound box 90 carried thereby may be readily detached from the tubular carrier 110 by removing the screw 112 and withdrawing the tone arm longitudinally from the carrier. After the tone arm and its sound box have been thus removed from the carrier 110, the screw 112 is again threaded into the tone arm, and the tone arm with the sound box 90 attached may then be stored within the casing 25 in a suitable space provided therefor on one side of the motor 50, as shown in dotted lines in Fig. 3 and in full lines in Figs. 4 and 5, the tone arm 100 being held in a fixed position by means of a spring clip 113 provided for this purpose, and rigidly secured against the inner surface of one of the side walls 30 by means of screws 114 or any other suitable means.

The ball 111 is positioned within a ring 115 and coaxially therewith, and is arranged to swing with respect thereto about a horizontal axis fixed with respect to the ring upon two diametrically opposed pivots 116 which are threaded through the ring 115 and which engage snugly in cylindrical sockets 117 provided therefor in the ball 111. The ring 115 is arranged to rotate about a fixed vertical axis upon a pin 120 rigid therewith and projecting downwardly therefrom, and which engages snugly but rotatively in a cylindrical socket 121 provided therefor in a lug 122 rigid with and projecting laterally from a rigid standard 123 which extends upwardly from and is rigid with a flat base plate 125. The base plate 125 is preferably rigidly secured to the upper surface of a flat rectangular base board 126, which lies entirely between the planes of the inner sur-

faces of the vertical side walls 29 and 30 and is rigidly secured to the main movable section 45 and is arranged in a plane perpendicular thereto and so that the upper surface of the base board 126 is in a plane with the lower or rear edge of the movable section 45, and so that the rear edge of the base board 126 is in a plane with the inner or under surface of the movable section 45. The base board 126 is preferably a sounding board. 75

The lug 122 is preferably extended laterally and upwardly and terminates at a point spaced slightly below the lower surface of the tubular carrier 110 when the sound box 90 is in an operative position upon the record, and so that when the sound box is moved laterally away from the record the carrier 110 will fall against the upper end of the lug 122 and will prevent the sound box from falling so low that the stylus 94 will engage against the upper surface of the top wall 35 of the casing 25. 80 85

For directing in a given direction the sound delivered from the tone arm 100 through the tubular carrier 110, the upper end of the standard 123 is provided with a hollow sound director 135 which may be integral with the standard 123 or rigidly secured thereto. This director is preferably flared exteriorly and interiorly from its central portion in opposite directions, and the inner end of the director is cupped and fitted snugly around the ball 111 and has an extreme diameter slightly less than the inner diameter of the ring 115 so that as the ring 115 is rotated about its vertical axis, it may pass over either edge of the cupped end of the director, the cupped end of the director being provided with two diametrically opposed recesses 140 arranged to receive the two pivots 116 respectively and alternately as the ring 115 is oscillated about its vertical axis. The inner end of the director 135 is preferably substantially conical in shape, both exteriorly and interiorly and is arranged so that its longitudinal axis is substantially parallel to the base board 126 and normally horizontal when the machine is in operation. Although the base plate 125 is preferably rigidly secured to the base board 126, the parts supported thereby are ordinarily sufficiently heavy to hold the base plate 125 in a stationary position without having it rigidly secured to the base board 126. 110 115 120

For amplifying and reversing the direction of the sound delivered through the director 135, a sound amplifier 145 is provided, which includes two vertical sounding boards 150 which are arranged in the angle between the base board 126 and the movable section 45 in planes perpendicular to the base board 126. These sounding boards diverge forwardly from the movable section 45 and the lower edges of these sounding boards are 130 135

rigidly secured to the upper surface of the base board 126, and the rear edges of these sounding boards are rigidly secured to the inner surface of the main movable section 45. The upper edges of these sounding boards extend from the main movable section 45 a short distance parallel to the base board 126 as at 151 and then are inclined forwardly and upwardly in straight lines as 10 at 152 and are joined by a flat rectangular top sounding board 155 which is rigidly secured to the upper edges of the sounding boards 150, and which is but slightly less in width than the width between the inner vertical surfaces of the side walls 29 and 30.

Spaced slightly in front of and parallel to the movable section 45 is a rectangular sounding board 156, the lower edge of which is rigidly secured to the upper surface of 20 the base board 126 and the upper edge of which is rigidly secured to the under surface of the top board 155. The vertical edges of this sounding board 156 are rigidly secured to the two surfaces of the sounding 25 boards 150 respectively. Arranged in front of the vertical sounding board 156 is a rectangular inclined sounding board 157, the lower edge of which is rigidly secured to the upper surface of the base board 126 and the upper edge of which is rigidly 30 secured to the inner surface of the sounding board 156. The vertical edges of this inclined board 157 are rigidly secured respectively to the inner surfaces of the two vertical sounding boards 150. The space 160 between the movable section 45 and the sounding board 156 is entirely closed and acts as a resonance chamber, and the space 161 between the inclined sounding board 40 157, the base board 126, and the vertical sounding board 156 is also entirely closed and also acts as a resonance chamber.

A needle receptacle 162, of any suitable construction, may be secured upon the upper 45 surface of the base board 126 and in the exterior angle between the movable section 45 and one of the vertical sounding boards 150.

For modifying the quality and volume 50 of the sound delivered into the sound amplifier through the director 135, a conical closure 165, made of felt or any other suitable material, is securely clamped upon one end of a normally horizontal plunger 166 which is coaxial with the director 135 and 55 which is arranged to reciprocate longitudinally in a sleeve or bushing 167 which extends snugly through the movable section 45 and the sounding board 156 and which is held securely in place in any suitable manner. The outer end of this plunger 166 extends rearwardly from the movable section 60 45 and is provided at its outer end with a knurled knob 168 rigidly secured thereby, and whereby the plunger may be conveniently moved longitudinally in either direction.

This knob 168 is so arranged that when the closure 165 is in engagement with the inner surface of the conical end of the director 135, as shown in dotted lines in Fig. 6, the inner surface of the knob 168 70 will be flush with the outer surface of the movable section 45 and will rest against the outer surface of the sleeve 167, as shown in dotted lines in Fig. 6. The plunger 166 is arranged to be held in its innermost position by means of a pin 169 which is secured in the plunger 166 and which slides in an internal slot 170 provided therefor in the sleeve 167 as the plunger 166 is moved from its outermost position towards its innermost 80 position.

When the plunger 166 is in its innermost position, the pin 169 will be in a position just inside the inner end of the sleeve 167, and by then rotating the knob 168 slightly the pin 169 will be moved out of alignment with the slot 170 and into engagement with the inner end of the sleeve 167 to prevent the accidental movement of the plunger 166 90 outwardly. The plunger 166 is thus locked in its innermost position when it is desired to fold the machine into its most compact form. When the plunger 166 is thus arranged in its innermost locked position, the knob 168 will be in the position shown in 95 dotted lines in Fig. 6 and in full lines in Fig. 1 and will serve as a convenient means for raising the amplifier from its inoperative to its operative position. By varying the distance of the closure 165 from the conical end of the director 135, corresponding variations in the quality and volume of the sound delivered into the amplifier may be produced.

For holding and locking the sound amplifier 145 either in an operative position, as shown in full lines in Fig. 3, or in an inoperative position, as shown in dotted lines in Fig. 3, the front or free edges of the movable top section 45 and the base board 126 are provided respectively with two marginal 110 undercut recesses 175 and 176 which are spaced equally from the axis of oscillation of the amplifier and which are arranged to receive alternately a tongue or flange 177 115 provided therefor along the inner edge of the auxiliary top section 38, the arrangement being such that when the tongue 177 is in the recess 175, the upper and lower surfaces of the movable section 45 and the auxiliary section 38 will be flush and in the same 120 planes respectively as the upper and lower surfaces of the fixed top sections 36 and 37, and when the tongue 177 is in the recess 176 the upper and lower surfaces of the base 125 sounding board 126 and the auxiliary top section 38 will be flush and in the same planes respectively as the upper and lower surfaces of the top sections 36 and 37. When the parts are in operative positions as 130 shown in Fig. 3 the top sections 36, 38 and

37 and the base board 126 form a substantially continuous sounding board.

For locking the sound amplifier 145 in its inoperative position, as shown in dotted lines in Fig. 3, a latch 185 is arranged against the outer surface of one of the side walls 29 to be moved longitudinally in either direction upon two headed screws 187 and 188 which extend loosely through two elongated slots 189 and 190 provided therefor in the latch and are threaded into the side wall 29. This latch 185 is provided with two horizontal fingers 190 and 191 integral therewith, which are arranged to be moved simultaneously into or out of engagement with a headed screw 195 threaded into one edge of the auxiliary section 38 and a screw 198 threaded into one edge of the main movable section 45, when the movable section 45 is closed. One end of the latch 185 is preferably turned outwardly to provide a handle 199 whereby the latch may be conveniently operated longitudinally. When the machine is in its folded and locked inoperative condition, as shown in Figs. 1 and 2, and it is desired to place the parts of the machine in their operative positions, the latch 185 is first moved towards the left, as shown in Fig. 1, to release the auxiliary top section 38 and the movable top section 45. These two sections are then swung outwardly as far as possible and the turntable 75, winding crank 65 and the tone arm 11 and its sound box 90 are taken out of the casing 25. The auxiliary top section 38 is then closed and the amplifier 145 is then swung inwardly until the free edge of the base board 126 rests upon the flange 177 of the auxiliary section 38. The latch 185 is then moved into an inoperative position to lock the auxiliary section 38 in position. The hub of the turntable 75 is then placed over the upper end of the turntable spindle 71, the screw 112 is removed from the larger end of the tone arm 100, and the larger end of the tone arm is inserted in the socket 109 of the carrier, and the screw 112 is then inserted through the slot 113 and threaded into the opening provided therefor in the tone arm. The knob 168 is then rotated until the pin 169 engages in the slot 170, whereupon the knob 168 is moved outwardly a suitable distance. The sound box 90 may now be adjusted either for a zig-zag record or for a hill and dale record, as the case may be, and the machine is ready for operation. By a process the reverse of the foregoing, the parts may be returned to their inoperative positions.

For controlling the speed of the motor 50, this invention provides an improved combined governor and brake, comprising a normally horizontal governor shaft 210 which is terminally supported for rotation in two brackets 211 which are rigidly secured respectively to two vertical posts 212 which are

terminally secured to the two horizontal motor plates 58 and 59. This governor shaft 210 is provided with worm 215 rigid therewith, which is arranged to be rotated by a worm gear 216 rigid with the turntable spindle 71. Arranged to slide longitudinally of the governor shaft 210 is a friction disc 220, and connecting the friction disc 220 and a collar 221 rigid with the shaft 210 are a plurality of springs 225 which have centrally a 70 and rigidly secured thereto respectively a corresponding plurality of fly balls 226, the arrangement being such that as the speed of the motor increases the balls 226 will fly outwardly and will draw the friction disc 80 85 90 95 100 105 110 115 120 125 130 135 140 145 150 155 160 165 170 175 180 185 190 195 200 205 210 215 220 225 230 235 240 245 250 255 260 265 270 275 ernor, the rod 232 is normally withdrawn until it is spaced slightly from the reduced end 242 of the rod 240, and the hollow shaft 230 is then adjusted longitudinally by rotating the knob 231 until the inner end of the hollow shaft 230 engages against the annular shoulder 242 and moves the rod 240 and the bracket 248 and friction pad 250 towards the friction disc 220 until the speed 10 of the motor is adjusted as may be desired. Any variation in the speed of the motor is then ordinarily accomplished by adjusting the hollow shaft 230 longitudinally. When, however, it is desired to stop the motor, 15 the outer knob 235 is pushed inwardly, and this brings the inner end of the rod 232 into engagement with the outer end of the reduced portion 241 of the rod 240 and forces the rod 240 rearwardly until the 20 friction pad 250 is pushed against the friction disc 220 with sufficient force to stop the motor. Ordinarily the rod 232 could be made to fit so snugly within the hollow shaft 230 that it would hold the brake pad 250 in any desired position of adjustment 25 to stop the motor without requiring the operator to continue pressing upon the knob 235. To provide a sufficient amount of friction between the rod 232 and the hollow shaft 230, the rod 232 might be split longitudinally throughout its inner portion and the two halves of the split portion might be normally spread apart so as to tend to separate when arranged within the hollow shaft 230 and thus produce the desired amount of friction. It is thought, however, that the rod 232 may be so snugly fitted within the hollow shaft 230 that it would not be necessary to have the rod 232 split as just described.

Although I have disclosed only one form in which this invention is embodied, it is to be understood that the invention is not limited to any particular construction, but might be embodied in various forms without departing from the spirit of the invention or the scope of the appended claims.

Having thus fully described my invention, I claim and desire to protect by Letters Patent:

1. A talking machine comprising a hollow movable sound amplifier, stationary hollow sound directing means arranged to deliver sound into said amplifier, and means carried by said amplifier and movable towards and away from said sound directing means for varying the effective area of the sound outlet of said sound directing means.

2. A talking machine comprising a casing having a normally substantially horizontal top wall including a main movable section arranged to swing about a normally horizontal axis and an auxiliary movable section arranged to swing about a horizontal axis,

a base wall secured to said main movable section and arranged to project in said casing when said main movable section is in a normally horizontal position, sound amplifying means arranged between said main movable section and said base wall and carried thereby, a tone arm support arranged within said amplifying means, a tone arm carried by said support, and sound reproducing means carried by said tone arm, said auxiliary movable section being normally arranged in the path of movement of said sound amplifying means but being movable out of said path to permit said sound amplifying means to be swung from an operative position projecting outside of said casing into a position within said casing.

3. A talking machine comprising a casing including a top wall having a section movable about a normally substantially horizontal axis from a substantially horizontal position into a substantially vertical position, a base wall secured to said movable section and so arranged that when said movable section is in a vertical position said base wall will lie in a substantially horizontal position and form a closure for a portion of said casing, sound amplifying means arranged between said base wall and said movable section, and sound reproducing means arranged to deliver sound into said amplifying means when said movable section is in an elevated position.

4. A talking machine comprising a casing including a wall comprising a main movable section and an auxiliary movable section, said movable sections being arranged to swing about substantially parallel axes respectively, and sound amplifying means secured to said main movable section, said movable sections being in substantially the same plane when in closed position.

5. A talking machine comprising a cabinet including a casing provided with a wall having two movable sections arranged to swing about substantially parallel axes respectively from opened positions to closed positions, said sections being substantially in the same plane when in closed positions, sound amplifying means secured to one of said sections and arranged to be entirely enclosed by said casing when said sections are in closed positions and said amplifying means being arranged to extend mainly outside of said casing when said movable section to which said amplifying means is secured is in an open or operative position.

6. A talking machine comprising a casing including a wall having a main movable section and an auxiliary movable section, said sections being arranged to swing about substantially parallel axes respectively, from closed positions to open positions and being substantially in the same plane when in closed positions, sound amplifying means

secured to said main movable section and projecting within said casing when said sections are in closed positions, and the major portion of said amplifying means projecting outside of said casing when said main movable section is in an open position, said auxiliary movable section being arranged in

a closed position and acting to support said amplifying means when said main movable section is in open position.

10

Signed at New York city, in the county of New York and State of New York, this 19th day of December, A. D. 1917.

ALFRED SONDEHEIMER.
